K. S. JOHNSON

ELECTRIC WAVE FILTER

Original Filed Dec. 31, 1920

Inventor:
Kenneth S. Johnson.
by *Swanson* Att'y.

UNITED STATES PATENT OFFICE.

KENNETH S. JOHNSON, OF JERSEY CITY, NEW JERSEY, ASSIGNOR TO WESTERN ELECTRIC COMPANY, INCORPORATED, OF NEW YORK, N. Y., A CORPORATION OF NEW YORK.

ELECTRIC WAVE FILTER.

Original application filed December 31, 1920, Serial No. 434,388, Patent No. 1,613,952. Divided and this application filed August 28, 1925. Serial No. 53,077.

This invention relates to electric wave filters adapted to be employed in a line such as a telephone line to permit the passage of currents of certain frequencies and to prevent the passage of currents of other frequencies and has for an object to improve the construction of such filters. This is a division of my previous application Serial No. 434,388, filed December 31, 1920, 5 patented January 11, 1927, No. 1,613,952.

A further object of this invention is to produce filters of various types which have the characteristics of types of filters in general already known, but which may be manufactured from a less amount of material thus reducing the cost and size of the filter.

In accordance with the invention, filter sections are employed which have similar impedances spaced apart in the direction of current propagation but having mutual impedance therebetween and which have one or more impedances located between the mutually related impedances. The effect of mutual impedance in general is to add impedance 20 to the common portion without the use of additional apparatus.

This invention is particularly related to the species of the invention in which the impedances having mutual impedance therebetween are included in arms of the filter which are in shunt to the line of current propagation.

The invention will be more clearly understood from the following detailed description taken in connection with the accompanying drawing in which

Fig. 1 represents schematically a filter composed of a plurality of similar filter sections embodying the invention, and

Figs. 2 and 3 show filters without mutual inductance which are electrically equivalent to the filter of Fig. 1.

Fig. 1 shows a filter of three sections, each of which comprises a series condenser C_1 and two shunt inductances L wound in parallel aiding relation on a magnetic core 45 4. By parallel aiding relation is meant that relation in which the coils are connected in parallel in such a direction that the flux produced by the current in one coil is added or increased by the current flowing in the other coil. The result of the mutual inductance between these two coils is a transformer action, as is well known, such a transformer can be represented by an equivalent T or Π network. Thus, Fig. 2 shows 50 a filter, each section of which is formed by replacing the two mutual inductive coils L by their equivalent T network in accordance 55 with the well known principles relating to transformers. Similarly, Fig. 3 is formed by the use of the equivalent Π network.

In Fig. 2, the transformer is replaced by two series inductances $L-M$ and a shunt inductance M where L represents the inductance of the coils and M the value of the mutual inductance therebetween. In Fig. 3, the transformer is replaced by a 60 series inductance

$$\frac{L-M^2}{M}$$

and two shunt inductances

$$\frac{L-M^2}{L-M}$$

Examination of Fig. 3 shows that it is a high pass filter section of the form shown in Fig. 8 of U. S. patent to G. A. Campbell 80 1,493,600 dated May 13, 1924. As is pointed out in that patent and in G. A. Campbell Patent 1,227,113, dated May 22, 1917, a filter having a plurality of sections, each having

a total series impedance Z_1 and a total shunt impedance Z_2 , will transmit a band of frequencies whose limits are determined by the equations:

5

$$\frac{Z_1}{Z_2} = 0,$$

and

$$10 \quad \frac{Z_1}{Z_2} = -4$$

In the filter of Fig. 3,

$$15 \quad Z_1 = \frac{j\omega \frac{L^2 - M^2}{M} \left(-j \frac{1}{\omega C} \right)}{j\omega \frac{L^2 - M^2}{M} - j \frac{1}{\omega C}}$$

$$Z_1 = \frac{j\omega (L^2 - M^2)}{M - C\omega^2 (L^2 - M^2)}. \quad \frac{2}{j\omega (L + M)} = \frac{2(L - M)}{M - C\omega^2 (L^2 - M^2)}$$

35 Assuming

$$\frac{Z_1}{Z_2} = 0, \text{ we get } \omega = \alpha \text{ or } f = \alpha$$

40 Assuming

$$\frac{Z_1}{Z_2} = -4, \text{ we get:}$$

$$45 \quad \omega^2 = \frac{L + M}{2C(L^2 - M^2)} \text{ or}$$

$$\omega = \frac{1}{\sqrt{2C(L - M)}}$$

$$50 \quad f = \frac{1}{2\pi\sqrt{2C(L - M)}}$$

Therefore, the filter of Fig. 3 and hence that of Fig. 1 also will transmit freely all frequencies from

$$55 \quad \frac{1}{2\pi\sqrt{2C(L - M)}} \text{ to } \alpha$$

It was shown in Patent No. 1,493,600 above referred to, that the attenuation of the filter section is infinite when:

$$60 \quad \omega = \frac{1}{\sqrt{L_1 C_1}} \text{ or } f = \frac{1}{2\pi\sqrt{L_1 C_1}}$$

Substituting in this equation

$$65 \quad f = \frac{1}{2\pi\sqrt{C \frac{(L^2 - M^2)}{M}}} = \frac{\sqrt{M}}{2\pi\sqrt{C(L^2 - M^2)}}$$

70 If this frequency of infinite attenuation is designated as f_α and the cut-off frequency be f_0 and the ratio $\frac{f_\alpha}{f_0}$ be α , it will be seen that

75 any desired sharpness of cut-off can be obtained by assigning a positive value to α more or less approaching unity.

If the core 4 be particularly designed to

$$20 \quad \begin{aligned} & j\omega \frac{L^2 - M^2}{M} \\ & = \frac{1 - C\omega^2}{1 - C\omega^2} \frac{L^2 - M^2}{M} \\ & = \frac{j\omega(L^2 - M^2)}{M - C\omega^2(L^2 - M^2)} \end{aligned}$$

$$25 \quad Z_2 = \frac{j\omega(L^2 - M^2)}{2(L - M)} = \frac{j\omega}{2}(L + M)$$

in which

$$j = \sqrt{-1},$$

L and M represent inductance, C capacity, and $\omega = 2\pi f$, f being frequency.

be free from hysteresis and eddy-current losses or an air core is used, there will be very little resistance effectively in the series arm as compared with a filter in which a physical inductance is used in the series arm since in the latter case the direct current resistance of the winding cannot be eliminated. It therefore follows that the maximum attenuation of the filter can be made to more nearly approach infinity by the use of mutual inductance.

This invention is not limited to the particular filter section shown but may be greatly modified, without departing from the spirit of the invention as defined in the appended claims. For example, other circuits such as series or parallel resonant circuits may be substituted for the condenser C or may be connected in shunt to the inductances L to give to other filter characteristics.

What is claimed is:

1. An electric network adapted to be connected between two sections of a circuit, said network comprising a condenser connected in series between said sections, and an inductance at each side of said condenser, said inductances being in shunt to said circuits and being so related as to have mutual inductance.

2. A wave filter section comprising a plurality of circuit branches disposed in series and shunt relationship with respect to the direction of wave propagation, reactive impedances associated in said branches, said impedances including a pair of coupled inductances included in two of said shunt branches which are separated by a series branch, said inductances effectively adding an inductance element to said series branch, the impedances and said element cooperating to permit the filter to pass freely a band of frequencies while attenuating other frequencies.

3. A wave filter section according to claim 2 in which said pair of coupled inductances are connected in parallel aiding relation.

coils included in two of said shunt branches which are separated by said series branch.

10

4. A wave filter section comprising a plurality of circuit branches arranged in series and shunt relationship to the direction of wave propagation, a condenser in a series

In witness whereof, I hereunto subscribe my name this 26th day of August, A. D. 1925.

KENNETH S. JOHNSON.
